United States Patent Office

Des. 206,266
Patented Nov. 22, 1966

206,266

ELECTRIC SHAVER

Alfred W. Madl, Mequon, Wis., assignor to John Oster
Manufacturing Co., Milwaukee, Wis., a corporation of
Wisconsin

Filed Jan. 13, 1966, Ser. No. 589

Term of patent 14 years

(Cl. D22—3)

FIG. 1 is a front perspective view of an electric shaver showing my new design;

FIG. 2 is a rear elevational view thereof on an enlarged scale;

FIG. 3 is a top plan view thereof;

FIG. 4 is a bottom plan view thereof;

FIG. 5 is a right side elevational view thereof; and

FIG. 6 is a left side view thereof.

The dominant features of the design reside in the portions shown in full lines on the drawing.

I claim:

The ornamental design for an electric shaver, as shown and described.
